7 Claims. (Cl. 80—56)

1

The present invention relates to the production of sheet or strip by rolling or by drawing through dies of the kind having opposing die surfaces whose separation is adjustable.

In such production the material entering between the rolls or opposing die surfaces may vary in thickness and other properties along its length and across its width as the result of previous treatment. In known rolling or drawing processes, these thickness variations are not entirely removed, and in fact other variations may be imposed by changes in the conditions of rolling or drawing.

At present the usual method of controlling the thickness of such sheet or strip issuing from a rolling mill is to measure continuously the thickness by means of a contact micrometer as the material emerges from the rolls, and manually to control the power operated roll screws to adjust the distance between the rolls whenever a consistent departure from the desired thickness is indicated. Generally the micrometer is placed some distance from the exit side of the rolls so that an indication of a change in thickness is not manifest until some time after the material has passed through the rolls. There is then a further delay whilst the operator becomes aware of the change and prepares to make an adjustment to the position of the rolls. Whilst making this adjustment the operator may quite likely over-correct with the result that the thickness is likely to vary about a mean value. A substantial length of off-gauge strip may thus pass through the mill.

One object of the present invention is to provide a new or improved method of controlling the thickness of the sheet or strip produced.

This new or improved method is based on the following facts. For convenience these facts and the description hereafter will be explained in relation to the passage of metal strip between rolls, but it will be readily apparent that they are equally applicable to strip of materials other than metal, to sheet of any suitable material, and to drawing through dies of the kind specified above.

The method of controlling the thickness of the strip in the present invention is dependent upon a relationship between the separating force between the rolls engendered by the strip passing through them, the roll setting, which is defined as the minimum distance between the rolls when no separating force is acting, and of the outgoing or issuing thickness. This relationship states that the separating force is proportional to the difference between the outgoing strip thickness and the roll setting. The factor of proportionality is the elastic constant of the mill commonly known as the mill spring. A corollary of this relationship is that if any increase in separating

2

force is accompanied by a decrease in roll setting equal to the change in separating force divided by the mill spring, the outgoing strip thickness will remain constant. Similarly, to maintain the outgoing thickness constant any decrease in separating force must be accompanied by an increase in roll setting equal to the change in separating force divided by the mill spring.

According to the invention this relationship between changes in the separating force and changes in the roll setting (die setting) is maintained constant so that the strip (or sheet) issues continuously from the mill with the same outgoing thickness.

Since differences in separating force may occur between one side of the strip and the other the method can be applied independently to each of the roll adjusting mechanisms which act on the two ends of the roll and thus ensure that the thickness of the two edges of the strip remain equal to one another. In this way uniformity of gauge is continuously preserved both along and across the strip.

When applied to the production of metal sheet or strip, the rolling or drawing can be effected when the metal is in either the hot or cold state.

In carrying out the invention load responsive elements which will respond to variations in the separating force are incorporated in the mill and linked by mechanical, electrical and/or hydraulic means with the roll adjusting mechanisms in such a way that the desired relationship between the changes in separating force and roll setting is continuously maintained.

One form of apparatus by which the present invention may be performed will now be described, by way of example only, with reference to the accompanying diagrammatic drawings, in which—

35 40 Figure 1 is a sectional side view of a rolling mill arranged for the performance of the invention, whilst

Figure 2 is an end view of the rolling mill shown in Figure 1, and

45 Figure 3 is a side view of a roll displacement meter which is responsive to the changes in the roll setting.

Figure 4 is a schematic drawing of the control arrangement for the apparatus.

50 Figure 5 is a view similar to Figure 2 of a form of mill using dies of the kind referred to above, and which may be used with the control arrangement in place of the rolling mill.

55 Referring now to the drawings, Figures 1 and 2 show a rolling mill somewhat similar to conventional mills used for the rolling of steel and comprising work rolls 10 supported in upper and lower bearing chocks 11 and 12 respectively which are themselves mounted in a mill stand.

13. The mill is, however, modified from conventional form by the replacement of the normal manually-operated roll adjusting screws by fluid-operated rams 14 operating in cylinders 15. The free end of each ram 14 bears on a cylindrical member 16, which may conveniently be of steel, and carries around its periphery a number of electrical resistance strain gauges 17, after the manner described in British Patent No. 626,206. Due to the interposition of the cylindrical members 16 between the upper chocks 11 and the roll adjusting rams 14, the resistance of the gauges 17 will be dependent upon the degree of compression of the members 16 and will, therefore, vary with changes in the separating force.

Changes in the roll setting are monitored by meters 18 one of which is mounted between the top of each of the upper chocks 11 and the underside of the top of the frame 13. As shown in detail in Figure 3, each meter 18 comprises a sliding rod 19 which passes through the base of a housing 20 and carries a cone 21 at its upper end. The rod 19 is preferably of a metal having a very low coefficient of thermal expansion. Two cantilever arms 22 are attached by one end to the top of the housing with their free ends in contact with the surface of the cone 21. The cantilever arms 22 carry electrical resistance strain gauges 23, which are arranged so that any flexing of the arms 22 due to movement of the rod 19 causes a change in the resistance of the gauges 23. The housing 20 is enclosed in a water cooling jacket 24. Thus variations in the distance between the ends of the rolls at which the particular meter is mounted causes a change in the resistance of the gauges 23.

Referring now to Figure 4, each strain gauge 17 is incorporated in a temperature compensated Wheatstone bridge network 25 (see British Patent No. 626,206), whilst the strain gauges 23 are incorporated in a similar network 26. Both networks 25 and 26 are supplied with alternating current at a frequency of 500 cycles per second from a source 27. The supply to network 25 is derived via a stabiliser 28 which ensures a substantially constant voltage input to the network 25 whilst the supply to network 26 is supplied via a voltage adjuster 29. The outputs from the bridges 25 and 26 are fed respectively to combined amplifiers and demodulators 30, 31 whose direct current outputs are combined in opposition and applied to a coil 32. It will be understood that the outputs of the networks 26 and 25 will be dependent upon the roll setting and the separating force. The voltage input to network 26 and the gain of amplifiers 30, 31 are adjusted so that with the desired outgoing thickness of material the outputs from demodulators 30, 31 are equal so that the voltage across the coil 32 is zero. Any change in separating force occasioned by a variation in outgoing thickness from the desired value will result in an out-of-balance voltage in the coil 32.

The coil 32 is wound on a core 33 and is movable within a polarising field provided by a permanent magnet 34 against the pressure of return springs 46. The core 33 is attached to the piston 35 of a differential fluid valve 36 which controls the supply of low-pressure fluid from an input 37 to one side or the other of a double acting piston 38 in normal manner. The pressure acting on piston 38 is modified by a fluid intensifier 39 which is connected by pipe 40 to

the rams 14. The intensifier acts so that the pressure of the piston 38 is amplified when increasing pressure is required to be applied to the rams 14 for adjusting the roll setting, whilst a reduction in pressure in the intensifier 39 is obtained when the piston 38 moves in the opposite direction. Thus an out-of-balance voltage in the coil 32 causes a movement of the piston 35, the direction of movement being dependent upon the polarity of the out-of-balance voltage which is itself dependent upon whether the thickness has increased or decreased. Movement of the piston 35 in turn produces a change in the roll setting which is in such a sense as to modify the output from network 25 and reduce the out-of-balance voltage to zero. In this manner the desired relationship between separating force and roll setting is substantially maintained.

Figure 5 shows a die stand 41 which can be used in a similar manner to the mill of Figure 1. The die stand 41 comprises upper and lower lips 42, 43 respectively, which may for example be of steel or metal carbide. The lower lip 43 is supported in a holder block 44 which is fixed relative to the die stand 41 whilst the upper lip 42 is carried by a holder block 45 so as to be movable relative to the other lip 43 for adjustment of the die setting (which corresponds to the roll setting in the case of the rolling mill). The die stand includes fluid operated rams 14 operating in cylinders 15, an interposed cylindrical member 16 carrying electrical strain gauges 17 and meters 18, all similar to those already described in conjunction with the rolling mill of Figures 1 and 2. The control arrangement is also similar to that described in connection with Figures 1 to 4, and further description is thought to be unnecessary.

Although in the above described arrangements the various meters have been arranged to produce electrical signals varying in accordance with variations in the separating force and the roll (die) settings, which then effect control by fluid means, it will be understood that alternatively the control may be effected by mechanical or fluid means alone or by combinations of these together and/or with electrical means.

It will be appreciated that in contrast to the normal existing method referred to above the monitoring of the thickness of the material is effected whilst it is in the roll or die gap, and correction is made with only the time delay inherent in the control mechanism.

We claim:

1. In apparatus for reducing the thickness of material, a thickness reducing member having opposed material engaging surfaces between which a separating force is established by the passage of material therethrough, means for adjusting the separation between said opposed material engaging surfaces in response to a control signal, means for continuously developing a first signal proportional to the separating force, means for continuously developing a second signal proportional to the separation between said opposed surfaces, and means for combining said first and second signals in predetermined proportions to give said control signal.

2. In apparatus for reducing the thickness of material, a thickness reducing member having opposed material engaging surfaces between which a separating force is established by the passage of material therethrough, control signal

responsive means for adjusting the separation between said opposed material engaging surfaces, means for developing a signal whose amplitude varies in correspondence to changes in said separating force, means for developing a further signal whose amplitude varies in correspondence to changes in said separation, variable gain signal amplifying means for amplifying said first mentioned signal and said further signal in different proportions, signal combining means for combining said first mentioned signal and said further signal after amplification, to give an output signal, and means for applying said output signal to said control signal responsive means.

3. Apparatus according to claim 2, in which the signal combining means comprises means for balancing the first mentioned signal against the further signal, and the relative gain of the signal amplifying means in respect of the two signals is such that said output signal is zero when the material leaving the apparatus is of predetermined thickness.

4. In apparatus for reducing the thickness of material, a thickness reducing member having opposed material engaging surfaces between which a separating force is established by the passage of material therethrough, control signal responsive means for adjusting the separation between said opposed material engaging surfaces, means for developing a signal whose amplitude is proportional to said separating force, means for developing a further signal whose amplitude is proportional to said separation, variable gain amplifying means for amplifying said further signal by a predetermined amount, further variable gain amplifying means for amplifying said first mentioned signal by an amount equal to a predetermined fraction of said predetermined amount, means for developing a control signal which is proportional to the difference between the amplified first mentioned signal and the amplified further signal, said control signal having a predetermined value when the material leaving the apparatus is of predetermined thickness, and means for applying said control signal to said control signal responsive means.

5. In apparatus according to claim 4, a supporting stand in which said thickness reducing member is mounted, and wherein said means for developing said further signal comprises a stress responsive member interposed between one of said opposed material engaging surfaces and said stand, an electrical resistance strain gauge mounted on said stress responsive member and responsive to variations in the stress applied to said stress responsive member, and means for applying an electric potential to said strain gauge, the resultant electric current through said strain gauge providing said further signal.

6. In apparatus according to claim 4, a supporting stand in which said thickness reducing member is mounted, and means for movably supporting at least one of said opposed material engaging surfaces in said stand, the relative position of said last mentioned means in said stand being determined by said control signal responsive means, and wherein said means for developing the first mentioned signal comprises a stress responsive member interposed between said stand and said means for movably supporting the one of said opposed material engaging surfaces, an electrical resistance strain gauge mounted on said stress responsive member and responsive to variations in the stress applied to said stress responsive member, and means for applying an elec-

tric potential to said strain gauge, the resultant electric current through said strain gauge providing said first mentioned signal.

7. In a rolling mill for reducing the thickness of material passing between a pair of work rolls, a supporting stand, one of said work rolls being fixed relative to said supporting stand and the other being movable relative to said supporting stand, a pair of chocks each housing one end respectively of the movable work roll, two members movably mounted in said stand and each adapted to apply pressure to one of said pair of chocks respectively whereby said movable work roll is urged towards the other work roll, electrically operated means for effecting movement of each of said movable members independently, two stress responsive members each interposed between one of said chocks and one of said movable members, two electrical resistance strain gauges each mounted on one of said stress responsive members, means for applying an electric potential to each of said strain gauges whereby the changes in current through each strain gauge is proportional to the variations in the separating force engendered between the work rolls at the corresponding end thereof by the passage of material through said work rolls, two further stress responsive members each interposed between one of said chocks and said supporting stand, two further electrical resistance strain gauges each mounted on one of said further stress responsive members, means for applying an electric potential to each of said further electrical resistance strain gauges whereby the changes in current through each of said further strain gauges is proportional to the variations in the distance between the corresponding ends of the work rolls, means for amplifying the changes of each of the currents through the strain gauges, the currents through said further strain gauges being amplified to a different degree from the currents through said first mentioned strain gauges, means for producing two control currents by combining in opposition each of the amplified currents from said further strain gauges with the amplified current from that one of the first mentioned strain gauges which is located at the corresponding end of said work roll respectively and means for applying each of the control currents to said electrically operated means for effecting movement of that movable member operating upon the corresponding end of the work roll.
